(57) **CLAIM**

The ornamental design for a clear way folding display shelf, as shown and described.

DESCRIPTION

The file of this patent contains at least one drawing executed in color. Copies of this patent with color drawing(s) will be provided by the Patent and Trademark Office upon request and payment of the necessary fee.

FIG. 1 is a front view of a clear way folding display shelf showing my new design;

FIG. 2 is a side perspective view thereof;

FIG. 3 is a front view thereof in closed condition;

FIG. 4 is a front view of a second embodiment of the clear way folding display shelf;

FIG. 5 is side perspective view of FIG. 4; and,

FIG. 6 is a front view of FIG. 5 in closed condition.

The environmental structures visible in the views form no part of the claimed design.
